DESIGN FOR A HANDBAG FRAME OR THE LIKE

Alfred F. Reilly, North Attleboro, Mass., assignor to Evans Case Company, a corporation of Massachusetts

Application August 25, 1939, Serial No. 86,895

Term of patent 3½ years

To all whom it may concern:

Be it known that I, Alfred F. Reilly, a citizen of the United States, residing at North Attleboro, county of Bristol and State of Massachusetts, have invented a new, original, and ornamental Design for Handbag Frame or the like, of which the following is a specification, reference being had to the accompanying drawing, forming a part thereof.

In the accompanying drawing Figure 1 is a perspective view of a handbag frame partially open showing my new design; Fig. 2 is a top plan view of a handbag frame showing my new design; Fig. 3 is an end elevation of a handbag frame showing my new design; Fig. 4 is a side elevation of a handbag frame showing my new design.

I claim as my invention:

The ornamental design for a handbag frame or the like, as shown.

ALFRED F. REILLY.
